CLAIM

The ornamental design for an electronic fuel injection
throttle body, as shown and described.

DESCRIPTION

FIG. 1 is an upper perspective view of an electronic fuel
injection throttle body design;

FIG. 2 is a top view of the design of FIG. 1;

FIG. 3 is a bottom view of the design of FIG. 1;

FIG. 4 is a first side view of the design of FIG. 1;

FIG. 5 is a second side view of the design of FIG. 1;

FIG. 6 is a front view of the design of FIG. 1;

FIG. 7 is a rear view of the design of FIG. 1; and,

FIG. 8 is a lower perspective view of the design of FIG. 1.

The broken lines shown in the drawings are included for the
purpose of illustrating the unclaimed boundary and/or
unclaimed portions of the electronic fuel injection throttle
body. The broken lines form no part of the claimed design.
